PARAFFIN GOPHER

Filed Oct. 16, 1930

UNITED STATES PATENT OFFICE

ROLEY C. McCARTER, OF RISING STAR, TEXAS

PARAFFIN GOPHER

Application filed October 16, 1930. Serial No. 489,195.

This invention relates to a device for use particularly in oil producing regions and has for one of its objects to provide, in a manner as hereinafter set forth, a tool adapted to be lowered into an oil well casing for the purpose of removing paraffin, etc. from the interior of the well casing.

Another important object of the invention is to provide a tool of the aforementioned character embodying a plurality of longitudinally extending runners or guides for preventing the tool from becoming caught on the joints of the casing when the tool is in use.

Another important object of the invention is to provide a paraffin gopher of the character described embodying a pair of pivotally mounted scrapers for operative engagement with the casing for cleaning said casing only when the tool is moved upwardly, said scrapers being free to swing upwardly to inoperative position when the tool is being lowered in the casing.

Another object of the invention is to provide a tool of the character set forth embodying means for permitting the escape of fluid from the upper side of the tool to the lower side of the said tool when the same is being raised in the casing thereby rendering it unnecessary to lift the fluid which may be disposed above the tool when raising said tool in the casing.

A further object of the invention is to provide a tool of the character set forth embodying means whereby escape of any gas which may be below the tool is permitted.

Other objects of the invention are to provide a paraffin gopher of the character set forth which will be simple in construction, strong, durable, efficient in operation and which may be manufactured at low cost.

All of the foregoing and still further objects and advantages of the invention may become apparent from a study of the following specification, taken in connection with the accompanying drawings wherein like characters of reference designate corresponding parts throughout the several views, and wherein:

Figure 1 is a view principally in elevation with parts broken away in section of a tool

constructed in accordance with this invention.

Figure 2 is a horizontal sectional view taken substantially on the line 2--2 of Figure 1 looking downwardly in the direction indicated by the arrows.

Figure 3 is a sectional view taken substantially on the line 3--3 of Figure 1 looking in the direction indicated by the arrows.

Figure 4 is a detail view in elevation of the perforated coupling whereby the supporting rod or cable is coupled to the tool.

Figure 5 is a detail view in perspective of a lower end piece which is adapted to be mounted on the tool when the well contains gas which it is necessary or desirable to permit to escape upwardly past the tool.

Referring to the drawings in detail, it will be seen that the reference numeral 1 designates an elongated tube having internally threaded opposite end portions and an enlarged intermediate portion 3 of polygonal cross section, as best seen in Figure 2 of the drawings. Pairs of longitudinally extending runners or guides 4 and 5 are mounted on the tube 1, said guides or runners having inwardly curved end portions which are anchored to the tube 1 above and below the enlargement 3 by any suitable means, such as welding or soldering. The guides or runners comprising each pair are mounted on diametrically opposite sides of the tube 1. Adjacent the enlargement 3, the guides or runners 4 are provided with notches or recesses in their inner edges for providing the horizontally disposed shoulders 6. A shaft 7 extends transversely through the enlargement 3 of the tube 1 and has its opposite end portions disposed for support in the eyes 8 provided in intermediate portions of the guides or runners 5. The rod 7 is provided with a tapered slotted head 10 which is countersunk in one of the eyes 8 and is further provided with a reduced threaded end portion 9 which is threaded into the other of the eyes 8, the reduced end portion providing a shoulder for abutting the said other eye 8, as clearly seen in Figure 2 of the drawings. A pair of substantially semi-circular scrapers 11 are hingedly mounted for swinging movement in a

100

vertical plane on the shaft 7 on opposite sides of the enlargement 3 and are engageable for rest on the shoulders 6 in a manner to support the scrapers in a horizontal position and prevent the same from swinging downwardly below the horizontal position but permitting the scrapers to swing upwardly from a horizontal position. The scrapers 11 have their adjacent edges recessed for the 10 reception of the enlargement 3 on the tube 1. The periphery of each of the scrapers 11 is disposed substantially concentrically with the outer edges of the runners or guides 4 and 5 and are provided with the notches 12 for 15 the reception of the runners or guides 4. The scrapers 11 are also recessed as at 13 for the reception of the eyes 8.

A pipe section 14 is threaded into the lower end portion of the tube 1 and is provided with aperitured transverse bar 15 in its lower end portion through which a rod 16 20 slidably extends. The rod 16 has connected to its lower end the depending, pointed nose 17 adapted for engagement with the lower end 25 of the pipe section 14 in a manner to close said lower end and form a check valve therefor. A washer 18 is fixed on the upper end portion of the rod 16 and a coil spring 19 encircles the rod 16 and has its lower end 30 engaged on the bar 15 and its upper end engaged with the washer 18 for yieldingly urging the rod 16 upwardly and seating the nose 17 against the lower end of the pipe section 14. A coupling 20 is threaded into the upper 35 end portion of the tube 1 and constitutes means for connecting the perforated pipe section 21 to the tube 1. The perforations in the pipe section 21 are designated by the reference numeral 22 and any desired number 40 of same may be provided. The upper end of the perforated tube 21 is closed by a plug 23 which is anchored therein in any suitable manner and has a threaded upper end portion 24 for engagement with the operating 45 rod or cable which supports the tool (not shown). The plug 23 is further provided with a flange 25 adjacent the threaded portion 24 for abutting engagement with the operating rod or cable.

50 In use, the tool is lowered into the well casing and as the same travels downwardly no scraping action will take place due to the fact that the scrapers are free to swing upwardly. However, when the tool is lifted in 55 the well casing, the scrapers 11 engage on the shoulders 6 and are supported thereon and the periphery edges of the scrapers will thus travel closely adjacent the wall of the well casing to effectively remove the paraffin 60 therefrom. The runners or guides 4 and 5 bridge or ride over the joints between the sections of the well casing and thus prevent the scrapers 11 from catching in said joints.

65 The column of fluid which may be above the tool in the well will, when the tool is drawn

upwardly in the well pass through the perforations 22 into the pipe sections 21, then through the coupling 20 and through the tube 1 into the lower pipe section 14 and the weight of the fluid will move the nose 17 away from the pipe section 14 and the fluid is thus permitted to escape into the well below the tool. 70

Should the tool be used in a well having an excessive quantity of gas which it is desired to permit to escape from below the tool, the pipe section 14 is removed from the lower end of the tube 1 and the pipe section 26 (see Figure 5) is substituted therefor. The pipe section 26 is provided with a tapered lower end portion 27 which is open at all times for the passage of gas from the well upwardly through the tube 1 through the coupling 20 into the upper pipe section 21 and out into the well again above the tool through the perforations 80 22. 85

It is believed that the many advantages of a tool constructed in accordance with this invention will be readily understood, and although the preferred embodiment of the invention is as illustrated and described, it is to be understood that changes in details of construction may be had which will fall within the scope of the invention as claimed. 90

What is claimed is:— 95

1. A tool of the character described comprising an elongated tube, guide runners mounted longitudinally on the tube and having intermediate portions disposed in spaced parallelism to the tube, and a pair of scrapers 100 hingedly mounted for swinging movement on the tube within the guide runners and having their scraping edges disposed substantially concentrically with the outer edges of the guide runners. 105

2. A tool of the character described comprising an elongated tube, guide runners mounted longitudinally on the tube and having intermediate portions disposed in spaced parallelism to the tube, and a pair of scrapers 110 hingedly mounted for swinging movement on the tube within the guide runners and having their scraping edges disposed substantially concentrically with the outer edges of the guide runners, the scrapers being further adapted for engagement with certain of the guide runners for limiting the swinging movement of the scrapers in one direction to a position substantially at right angles to the tube. 115

120 3. A tool of the character described comprising an elongated tube, guide runners mounted longitudinally on the tube and having inwardly curved end portions rigidly secured to the tube, the intermediate portions of the guide runners being disposed substantially in spaced parallelism to the tube, certain of the guide runners being provided with shoulders on their intermediate portions, and a pair of scrapers hingedly mounted for 125 130

swinging movement on the tube within the guide runners and having notches in their scraping edges for the reception of the guide runners, said scrapers engageable for rest on the shoulders for supporting said scrapers against swinging movement in one direction in a position substantially at right angles to the tube.

4. A tool of the character described comprising an elongated tube, guide runners mounted in spaced parallelism on the tube and having inwardly curved end portions rigidly secured to the tube, certain of the guide runners being provided with notches on their inner sides providing horizontally disposed shoulders on intermediate portions of said certain guide runners, horizontally aligned eyes on intermediate portions of the other guide runners in the horizontal plane of the shoulders, a shaft extending transversely through the tube and having its end portions engaged in the eyes, a pair of substantially semi-circular scrapers hingedly mounted on the shaft for swinging movement in a vertical plane on opposite sides of the tube and within the guide runners, the scraping edges of said scrapers having recesses therein for the reception of the guide runners, said scrapers further having their scraping edges disposed substantially concentrically with the outer edges of the guide runners, the scrapers being further adapted for engagement for rest on the shoulders for limiting the swinging movement of the scrapers in one direction and in a position substantially at right angles to the tube.

5. A tool of the character described comprising an elongated tube, adapted for vertical movement in a well casing, guide runners mounted longitudinally on the tube, scrapers hingedly mounted for swinging movement on an intermediate portion of the tube within the guide runners, and engageable with the guide runners for limiting the swinging movement of the scrapers in one direction in a position substantially at right angles to the tube, a pipe section connected to the lower end of the tube and depending therefrom a check valve supported for vertical reciprocation on the pipe section and engageable with the lower end thereof in a manner to control the passage therethrough, spring means operatively connected with the check valve for yieldingly retaining the same in closed position, a perforated pipe section coupled to the upper end of the tube, and means on the perforated pipe section for coupling an operating rod thereto.

In testimony whereof I affix my signature.

60 ROLEY C. McCARTER.
